UNITED STATES PATENT OFFICE.

FRANK HARVEY AND JOHN KANE, OF RENOVO, PENNSYLVANIA.

CAR-COUPING.

SPECIFICATION forming part of Letters Patent No. 493,998, dated March 21, 1893.

Application filed January 17, 1893. Serial No. 458,732. (No model.)

To all whom it may concern:

Be it known that we, FRANK HARVEY and JOHN KANE, citizens of the United States of America, residing at Renovo, in the county 5 of Clinton and State of Pennsylvania, have invented certain new and useful Improvement in Car-Couplings; and we do hereby declare the following to be a full, clear, and exact description of the invention, such as 10 will enable others skilled in the art to which it appertains to make and use the same, reference being had to the accompanying drawings, and to the letters of reference marked thereon, which form a part of this specification.

15 This invention relates to improvements in car couplings; the same being designed, more especially, as an improvement upon our patent issued December 30, 1890, No. 443,916; and the present invention consists in the im- 20 proved form of latch and drawhead, as will be hereinafter fully set forth, and particu- 25 larly pointed out in the claims.

In the accompanying drawings, Figure 1 is a horizontal sectional view of a car-coupling constructed in accordance with our invention. Fig. 2 is a vertical section. Fig. 3 is a front elevation, showing the means em- 30 ployed for raising the latch. Fig. 4 is a side elevation of the latch detached. Fig. 5 is a

35 sectional view through the line $x-x$. The draw-head, A, at the end of the draw- 40 bar A' has pivoted thereto the coupling- hook B, which is substantially as shown in our prior patent referred to. One side of the draw-head is continued toward the center, as shown at C, and against this projection 45 bears the catch F. The opposite side of this catch bears against a web, D, formed be- 50 tween the two pieces which make up the draw-bar.

G designates a vertical web, which is formed between the members of the draw- 55 bar rear of the web D and on the opposite side therefrom, and to this web is pivoted the latch, said latch being bifurcated to embrace the web. The latch is bent so as to 60 locate its forward portion, which lies be- 65 tween the guides C and D, in the center of the draw-bar and on a line therewith. At 70 the forward end of the latch is attached an

eye, i, which is connected by a link or connecting bar to a crank-shaft I, carried by the end of the car.

The draw-bar is connected to the car in any suitable manner, preferably by what is 55 known to the trade as the "Graham patent rigging," and to apply our improvement to this rigging it is necessary to have a free space from the forward end, or open head, of the draw-bar to the rear end, into which 60 the headed connecting bar can be passed, and by locating the web G to one side of the center the result is readily accomplished; moreover, the bearing of the latch can be 65 more readily cleansed of obstructions which are liable to accumulate between the upper and lower pieces of the draw-bar; and fur- 70 ther, by providing the guides C and D the latch is more thoroughly braced at its for- 75 ward end.

The forward portion of the latch is chan- 75 neled on its under side so that only the side edges rest upon the draw-bar.

Having thus described our invention, what we claim as new, and desire to secure by Let- 75 ters Patent, is—

1. The combination in a car-coupling, of a draw-bar carrying a latch the rear end of which is pivoted to a web located to one side of the center of the draw-bar, together 80 with bearing walls C and D between which the latch moves, the forward end of the latch being adapted to engage with the coupling- hook, substantially as shown, and for the pur- 85 pose set forth.

2. The combination in a car-coupling, of a draw-bar carrying within the same a verti- 90 cally moving latch, the rear end of said latch being bifurcated to embrace a vertical web G, to which it is pivoted, together with 95 guide C and D provided with straight walls against which the forward portion of the latch bears, the center portion of the latch being bent to locate the ends out of line, sub- 100 stantially as shown, and for the purpose set forth.

3. In a twin jaw car coupling, a draw-head having one side extended inward to form a guide for the latch, webs D and G located on opposite sides of the draw-bar, a pivoted 100

coupling hook B adapted to be engaged by the forward end of the latch, the forward portion of the latch lying between the guides or bearings D and C and the rear portion 5 being bent so as to be pivoted to the web G, substantially as shown and for the purpose set forth.

In testimony whereof we affix my signatures in presence of two witnesses.

FRANK HARVEY.
JOHN KANE.
